Primary Examiner — Janice Hallmark*Assistant Examiner* — Omeed Agilee(74) *Attorney, Agent, or Firm* — Womble Bond Dickinson (US) LLP(57) **CLAIM**

The ornamental design for a carton blank, as shown and described.

DESCRIPTION

The sole drawing FIGURE is a plan view of a carton blank showing our new design.

All evenly-spaced broken lines are for environmental purposes only and do not form part of the claimed design.

1 Claim, 1 Drawing Sheet(56)
